ATTORNEYS

UNITED STATES PATENT OFFICE.

SEWARD H. CALKINS, OF NEW YORK, N. Y.

DIVIDER AND REINFORCING STRIP.

Application filed January 19, 1921. Serial No. 438,439.

To all whom it may concern:

Be it known that I, SEWARD H. CALKINS, a citizen of the United States, and a resident of the city of New York, Long Island City, 5 borough of Queens, in the county of Queens and State of New York, have invented a new and Improved Divider and Reenforcing Strip, of which the following is a full, clear, and exact description.

10 This invention relates to strips for concrete work and particularly for terrazzo coatings and has for an object to provide an improved construction wherein the strip may be bent to the desired shape easily and then 15 anchored correctly.

Another object in view is to provide a strip which will act as a dividing member for dividing concrete work into sections and at the same time act as a reinforcement for 20 the divided sections or blocks.

A further object of the invention is to provide a dividing and reenforcing strip in which an uninterrupted metal plate is used for the dividing member and associated with 25 anchors for maintaining the plate at the proper depth.

In the accompanying drawings—

Figure 1 is a fragmentary top plan view of a floor showing a "terrazzo mosaic" construction and illustrating how the invention 30 appears when in use.

Figure 2 is a top plan view on an enlarged scale of an unfinished section of terrazzo work with the strip embodying the invention shown in position.

Figure 3 is a sectional view through Figure 2 approximately on line 3—3.

Figure 4 is a fragmentary perspective view of an anchor disclosing certain features 40 of the invention.

Figure 5 is a perspective view showing one end of a strip embodying certain features of the invention.

In the construction of concrete floors a 45 concrete aggregate is applied to a given space and spread out in such a manner as to produce the desired smooth surface. Where the floor is comparatively large the concrete is usually divided into blocks by a line of 50 breakage but this line is not seen on the surface as ornamental grooves are provided in line with the line of breakage. In producing very fine floor effects, as for instance, providing a "terrazzo mosaic" difficulty is 55 encountered as this form of flooring is usually provided with certain sections having

different coloring from the remaining sections. The same is true of ceilings, walls or other surfaces. In providing a terrazzo wall, floor or other surface the aggregate 60 should be placed in position at approximately the same time over the entire surface in order that it may properly cure simultaneously and thereby be properly ground. This grinding of the surface must take place at 65 a certain stage in the curing so as to produce a proper surface. If the grinding action is carried on too soon, more of the surface will be ground away than desirable and a comparatively high polish will not be presented 70 while if the surface is too old it will be hard to grind properly within a reasonable time. By the present invention, means have been provided which will permit different colored blocks, stripes or sections to be applied at the 75 same time and, consequently, to cure simultaneously so that the entire surface may be ground at the same time with equally good results on all parts of the floor.

Referring to the accompanying drawings 80 by numerals, 1 indicates a section of flooring constructed according to the present invention. In constructing this floor it will be noted that there is provided blocks 2 of one color having an interior section 3 of a second color and a border 4 of another color. 85 These sections and borders may be of any shape desired and the aggregate forming these sections is held in proper place by various strips 5. These strips 5 may be of brass 90 or other suitable material of any desired height with a row of apertures 6 arranged preferably along a central line. Positioned in these apertures are anchors 7 having bent ends 8, said ends 8 acting as anchoring means 95 for preventing adjacent blocks or sections from separating during the curing action. The adhesive quality of the aggregate in connection with the strips 5 also assist in holding the blocks in proper position as the 100 shrinkage is very small. In addition to acting as anchors for holding the adjacent blocks together the member 7 acts as supporting anchors for the dividing strip 5 and limits its downward movement 105 into the base concrete 9 which is positioned on a suitable foundation 10 and which receives the aggregate 11. Preferably, the foundation 10 is provided and formed in any desired manner so as to produce the proper thickness and a substantially 110 level surface. The base 9 is then applied to

the foundation 10 and is spread out so as to have a substantially even upper surface.

After the concrete base has been properly placed in position and while it is still green, 5 the strips 5 are forced downwardly therein until the anchors 7 engage the upper surface thereof. After all of the strips 5 have been placed in position the aggregate 11 is then deposited in the various places according to 10 the color design desired and the aggregate is then rolled so that it will be compressed to the proper consistency. In this rolling action the strips 5 will be forced downwardly to an undesirable extent except for 15 the supporting anchors 7 which hold the same in proper position while allowing the rollers to compress the aggregate between the various strips.

By the use of the anchors 7 a proper anchoring support is provided for the strips 5 while at the same time any of these anchoring devices may be easily removed where a transverse strip 5' is to be provided and where said strip would interfere with the 20 member 7. It will also be noted that by reason of the fact that the strip 5 is one continuous strip having an upper and lower straight edge, the same may be easily bent 25 into a circle or into any other shape desired.

easily and without interfering with the anchors 7 as said anchors are not applied until after the strips have been bent to the desired shape.

What I claim is:—

1. A dividing and reenforcing strip comprising a flat metal strip having straight upper and lower edges and a row of apertures arranged on a central line between said edges and an anchoring member for each of said apertures extending loosely therethrough and formed with bent ends acting as anchoring or gripping means for locking adjacent sections of the floor together.

2. A strip acting as a divider for terrazzo or plastic composition floors comprising a substantially flat strip of metal having apertures formed therein intermediate its upper and lower edges, and a tie rod extending through said apertures and projecting laterally from one side of said strip.

3. A strip acting as a divider for terrazzo or plastic composition floors comprising a substantially flat strip of metal having apertures formed therein, and a tie rod extending through said apertures and projecting laterally from one side of said strip, said tie rod being bent to form an anchor.

SEWARD H. CALKINS.
